ADAM NEWKUMET, OF PHILADELPHIA, PENNSYLVANIA.

Letters Patent No. 86,243, dated January 26, 1869; aniedated January 18, 1869.

IMPROVEMENT IN MOULDING CRUCIBLES AND POTTERS' WARE.

The Schedule referred to in these Letters Patent and making part of the same.

To all whom it may concern:

Be it known that I, ADAM NEWKUMET, of Philadelphia, in the county of Philadelphia, in the State of Pennsylvania, have invented a new and improved Apparatus for Moulding Crucibles and Potters' Ware; and I do hereby declare that the following is a full and exact description thereof, reference being had to the accompanying drawings, and to the letters of reference marked thereon, making a part of this specification, in which—

Figure I is a vertical section through line A B, (see Fig. III,) and represents the apparatus with the variable slide-former P expanded, and lowered into the mould N, for the purpose of shaping the interior surface of the crucible or other vessel to be moulded.

Figure II is a vertical section through line C D, (see Fig. I,) representing the variable former P in a raised or elevated position, in order to permit the removal of the formed vessel from the mould N.

Figure III represents a horizontal section of the slide-frame K, mould N, and variable former P, when fully expanded, as shown in Fig. I.

Figure IV represents a side elevation of the variable slide-former P, consisting of two halves, the latter in expanded position.

Figure V is a plan of the slide-former P, in its contracted position.

Similar letters of reference indicate corresponding parts in the several figures.

My invention uses the known device of forming vessels of clay, or other plastic material, by means of a mould fixed in the centre of a circular revolving table.

But, instead of using the human hand, or a piece of wood or metal, for pressing the plastic material against the inner side of the mould, I use a variable slide-former, arranged to be lowered, or placed inside the mould, and, at the same time, expanded, in order to form the interior of the vessel to the desired shape, and which, by contracting it, permits its lifting out of the mould again.

My apparatus for manufacturing crucibles or potters' ware, is composed of three different devices:

First, of the device to effect the lowering and lifting in and out of the mould of the former P.

Second, of the device to produce *vice versa* rotary motion to the slide-former and mould.

Third, of the device to effect the expansion and contraction of the slide-former.

To enable others skilled in the art to understand my invention, I will proceed to describe its construction and operation.

First, the device, to effect the lowering and lifting of the variable slide-former in and out of the mould, consists of the slide-frame K, (see Fig. I;) of the horizontal spur-wheel shaft t, with the spur-wheels h h', and the hand-wheel x fastened to it; of the screw s, fixed to the cross top-piece of the slide-frame K; of the nut

f, fitting screw s, and forming the centre of the hand-wheel w; of the grooved hub o, (fitting spindle q loosely,) containing the joints c c' of the connecting-rods y y', the latter transmitting motion to the slides, of which the former P consists, by means of the pins c c' passing through the fork-projections, seen at the top of each former-slide, and the connecting-rods y y'; of the circular strap u, surrounding hub o, and forming a portion to the hand-wheel w, by means of the studs v v', and of the pin r, seen below the slide-frame K, (see Fig. I,) regulating or stopping the slide-frame K, when lowered, at such a point as to affect the thickness of the bottom of the vessel to be moulded.

The vertical sides of the slide-frame K are provided with a vertical gear, corresponding with the pitch of the spur-wheels h h', fastened to the shaft t, in line with the vertical gears, to permit transmission of motion to slide-frame K, whenever hand-wheel x is forced to turn.

As all the above-named parts are in direct connection, from top part of slide-frame K down to the joints c c' seen at the top of the slides of the former P, any motion given to wheel x will operate the spindle q, with parts fastened to it, and those in connection with such, up or down, according to the direction the wheel x had received, by means of which the lowering and lifting of the variable slide-former P are effected.

At its lower part, P is fastened to the lower end of the spindle q by means of pin z, which passes through both slides of the former P and the spindle q. This connection keeps the former-slides with their inner face in contact, but allows them to be moved against each other, and *vice versa*.

Second, the device to produce contrary rotary motions to the slide-former P and mould N against each other, consists of the circular revolving mould-table T, fastened to the vertical spindle n; of the bevel-gear i i', one wheel of which is fastened to spindle n, its match i, and the pulley H to the horizontal shaft g of the belt m; of the pulley L, and bevel-wheel R', both fastened to the upper horizontal shaft Y of the bevel-match R upon spindle q, its top end being so arranged as to permit the lifting and lowering of the spindle without causing bevel-wheel R to move in such direction, and also to transmit motion, that is, revolving motion, to spindle q; of the mould N, constructed of two or more parts, fastened upon the centre of the circular revolving table T by means of the screws d' d, the hook e, in connection with pin p, e and p holding the mould-parts together against the circular projection seen on the top of the revolving table T. The lower part of the mould N, with the lower part of the slide-former P, and the projection seen upon centre-table T, produce the bottom of the vessel to be formed.

Any motion given to the belt m will move or turn both pulleys, H and L, in like direction; but, transmitting such motion, by means of the bevel-gears, to

the spindle *q* and circular mould-plate or table *T*, it causes the table *T* to revolve in contrary direction to the spindle *q*, and therefore the variable slide-former *P* too.

Third, the device to effect the expansion and contraction of the variable slide-former *P* consists of the screw *s*, fastened to the top cross-piece of the slide-frame *K*; of the corresponding nut *f*, forming the centre of the hand-wheel *w*; of the grooved hub *o*, with the pin-holes *c c'*, and the surrounding strap *u*, the latter being fastened to the nut hand-wheel *w* by means of the studs *v v'*; of the inclined rods *y y'*, connecting the former-slides by means of the pins *c c'*, and the fork-projections, seen at the top of the former-slides, through which pins *c c'* pass.

To effect the contraction of the slide-former *P*, nut *f* is turned upwards by means of turning the hand-wheel *w*, causing strap *u* and hub *o* to follow, as well as the connecting-rods *y y'*. This movement forces the rods *y y'* in the upward position, as indicated by the red lines seen in Fig. I, and draw thereby the former-slides toward each other. The expansion of the former-slides is effected by turning the nut *f* toward the mould *N*, as shown in Fig. I.

Fig. V shows an oblong opening in the top part of the former-slides, fitting the diameter of the spin-

dle *q*, whereby a bearing is given to the slides of the former, and thereby steadiness.

The plate *W*, seen above the mould *N*, with its openings on its periphery, opposite each other, fitting over the fork-projections fastened to the top of the former-slides, has the object also to prevent the slides of the formers from being forced apart while in motion.

The oblong opening, seen at the top of the former-slides, has also the object to permit the expansion of the slides of the former, without interfering with the spindle *q*.

Having now described my invention, I desire to secure, by Letters Patent, the following claims:

1. The variable slide-former *P*, constructed as described, in combination with the arrangement, by means of which the degree of contraction and expansion of the former-slides, or their positions to each other, is effected, substantially and for the purposes specified.

2. The revolving variable slide-former *P*, and vertically-sliding frame *K*, in combination with a divisible mould, fastened to a reverse-revolving table, substantially as described, and for the purpose specified.

Witnesses: AD. NEWKUMET.
